UNITED STATES PATENT OFFICE.

WILLIAM F. BOSSERT, OF UTICA, NEW YORK, ASSIGNOR TO THE BOSSERT ELECTRIC CONSTRUCTION COMPANY, OF UTICA, NEW YORK.

DESIGN FOR A PIPE COUPLING OR NIPPLE.

SPECIFICATION forming part of Design No. 35,204, dated October 22, 1901.

Application filed April 23, 1901. Serial No. 57,142. Term of patent 14 years.

To all whom it may concern:

Be it known that I, WILLIAM F. BOSSERT, residing at Utica, in the county of Oneida and State of New York, have invented and produced a new and original Design for a Pipe Coupling or Nipple, of which the following is a specification.

and *o*, and interiorly, as *f*. The rounding curve *f* continues inwardly toward the region *g* and outwardly toward the body *b*. The curve *f* surrounds a circular aperture, which circular aperture is of less diameter than that of the region *g*.

What I claim is—

The design for a pipe coupling or nipple, as herein shown and described.

In testimony whereof I have signed my name to this specification, in the presence of two subscribing witnesses, this 16th day of April, A. D. 1901.

WILLIAM F. BOSSERT.
